UNITED STATES PATENT OFFICE.

JAMES HARRISON, OF EAST HAMPTON, CONNECTICUT.

IMPROVEMENT IN DOOR-BELLS.

Specification forming part of Letters Patent No. 138,151, dated April 22, 1873; application filed December 4, 1872.

To all whom it may concern:

Be it known that I, JAMES HARRISON, of East Hampton, in the county of Middlesex and State of Connecticut, have invented a new and Improved Gong House-Bell; and I do hereby declare the following to be a full, clear, and exact description thereof, which will enable those skilled in the art to make and use the same, reference being had to the accompanying drawing forming part of this specification, in which drawing—

Figure 1 represents a horizontal section of my invention in the plane $\alpha\alpha$, Fig. 2, the bell being indicated in dotted lines. Fig. 2 is a vertical central section of the same.

Similar letters indicate corresponding parts. This invention consists in arranging the pivot on which the hammer or clapper swings inside the bell, and on a radial line drawn through the center support of the bell, which, running at right angles to the direction of the pull-wire in such a manner that when the pull-wire is drawn out, the hammer, which is situated on the outside of the bell, is caused to strike said bell above the center support, and when the pull-wire is released the hammer descends and strikes a second blow beneath the center support. The shank of the hammer connects with a spring, which serves to keep the hammer clear of the surface of the bell, and which, also, increases the force of the second blow of said hammer. This spring also acts on an eccentric formed on the shank of the hammer, and provided with a groove to retain the end of the spring in position.

In the drawing, the letter A designates a gong-bell, which is secured to a support, B, fastened in a bed-plate, C. From this bed-plate rises a stud or pivot, a , which forms the fulcrum of the hammer D. The shank of the hammer extends beyond said fulcrum-pin, and to its inner end is secured the pull-wire E, the hammer itself being situated on the outside of the bell.

By referring to Fig. 1 of the drawing, it will be noticed that the pivot a is situated on a radial line drawn through the center support B, and running at right angles, or nearly so, to the direction of the pull-wire E, the connection of said pull-wire with the shank of the hammer being made at a point between the

center support of the bell and the pivot a . By this arrangement the hammer is free to swing up and down, and to strike the outside of the bell both on its upward and on its downward motion, the upward blow of the hammer being produced by pulling the wire E, and the downward blow by the weight of the hammer, which causes the same to descend as soon as the pull-wire is released.

By examining the drawing, it will be readily understood that unless the relative position of the pivot a , the center support, and the pull-wire is preserved, as above described, the hammer could not be made to strike an up-and-down blow on the outside of the bell; and it must be further remarked that, if the hammer strikes the bell on the outside, it is much less liable to injure the bell than it is if it strikes on the inside, and for this reason bells constructed according to my invention are much more durable than bells on which the hammer strikes from the inside.

The shank of my hammer D is provided with an eccentric, b , through which passes the pivot a , the hammer being secured to the largest radius of said eccentric, while the arm to which the pull-wire is attached extends from the smallest radius of said eccentric. On the circumference of this eccentric bears a spring, d , which is fastened at one end to a stud, e , rising from the bed-plate, and which winds one or more times around the center support of the bell. The loose end of said spring rests in a groove, f , formed in the eccentric b , and intended to prevent the spring from getting displaced.

If the wire E is pulled so as to raise the hammer, the loose end of the spring travels up toward the highest part of the eccentric, and the spring is strained. If the pull-wire is released, the spring assists in carrying the hammer down, and the force of the down blow is increased. As the hammer rebounds from the down blow it is caught by the spring and retained clear of the body of the bell, in the position shown in Fig. 1.

It will be readily seen that the connection between the spring and the shank of the hammer could be modified in various ways, and I do not wish to be confined to the precise mode of attaching the spring, as shown in the draw.

ing. Furthermore, in my bell the action of the hammer does not depend upon the spring, and if the spring should break the hammer would still continue to act; but its down blow would, in this case, depend solely upon the weight of the hammer. This effect is due mainly to the relative position of the pivot *a*, the center support of the bell, and the pull-wire, as previously described.

What I claim as new, and desire to secure by Letters Patent, is—

1. The combination of the spring *d* with the

shank of the hammer *D*, the pull-wire *E*, and the bell *A*, substantially in the manner and for the purposes set forth.

2. The eccentric *b*, formed on the shank of the hammer *D*, and provided with a groove, *f*, in combination with the spring *d*, pull-wire *E*, and bell *A*, all constructed and operating substantially in the manner shown and described.

JAMES HARRISON.
